(57) **CLAIM**

The ornamental design for a storage container, as shown and described.

DESCRIPTION

FIG. 1 is a front perspective view of a storage container illustrating an embodiment of a new design in an assembled configuration;

FIG. 2 is another front perspective of the storage container of FIG. 1 illustrating the new design in an exploded view; FIG. 3 is another front perspective view of the storage container of FIG. 1 illustrating the new design in another exploded view, where the front flap of the storage container of FIG. 1 is open;

FIG. 4 is a front view of the storage container of FIG. 1 illustrating the new design;

FIG. 5 is a rear view of the storage container of FIG. 1 illustrating the new design;

FIG. 6 is a left-side view of the storage container of FIG. 1 illustrating the new design;

FIG. 7 is a right-side view of the storage container of FIG. 1 illustrating the new design;

FIG. 8 is a top view of the storage container of FIG. 1 illustrating the new design;

FIG. 9 is a bottom view of the storage container of FIG. 1 illustrating the new design;

FIG. 10 is a front view of the storage container of FIG. 1 illustrating the new design with two units interlocked;

FIG. 11 is a section view of the storage container of FIG. 1 illustrating the new design; and,

FIG. 12 is a rear view of the storage container of FIG. 1 illustrating the new design.
